Primary Examiner — Khawaja Anwar*(74) Attorney, Agent, or Firm* — Taro Yaguchi(57) **CLAIM**

The ornamental design for a anti vibration glove, as shown and described.

DESCRIPTION

The patent or application file contains at least one drawing executed in color. Copies of this patent or patent application publication with color drawing(s) will be provided by the Office upon request and payment of the necessary fee.

1. Anti vibration glove

1.1 : Front

1.2 : Back

1.3 : Right

1.4 : Left

1.5 : Top

1.6 : Bottom

1.7 : Enlarged

1.8 : Enlarged

1.9 : Perspective

Design 1: the color, red, represents non-claimed portions of claimed design and forms no part of claimed design.

**1 Claim, 9 Drawing Sheets
(9 of 9 Drawing Sheet(s) Filed in Color)**(56)
